CLAIM

The ornamental design for a beverage bottle, as shown and described.

DESCRIPTION

FIG. 1 is a perspective view of an embodiment of a beverage bottle in accordance with my new design.

FIG. 2 is a front view of the beverage bottle shown in FIG. 1. The back view is similar and not separately illustrated herein.

FIG. 3 is a side view of the beverage bottle shown in FIG. 1. The opposite side is similar and not separately illustrated herein; and,

FIG. 4 is a top view of the beverage bottle shown in FIG. 1. The broken line showing of the environment is for illustrative purposes only and forms no part of the claimed design.
